EXTRACTION OF AROMATIC AND SULFUR COMPOUNDS

Carl E. Johnson, Griffith, and Arthur A. Harban,
Hammond, Ind., assignors to Standard Oil
Company, Chicago, Ill., a corporation of Indiana

Application September 30, 1949, Serial No. 118,745

13 Claims. (Cl. 196—14.35)

1

This invention relates to the extraction of aromatic hydrocarbons and organic sulfur compounds from mixtures of either or both thereof with aliphatic hydrocarbons, for example, such mixtures as occur in various processed or unprocessed petroleum oils. More particularly, this invention relates to processes for the selective extraction of aromatic hydrocarbons and organic sulfur compounds from oils comprising aliphatic hydrocarbons by the employment of certain 10 amine salts of sulfonic acids as selective extraction solvents.

Numerous so-called selective solvents have been proposed for removing aromatic and/or organic sulfur compounds from their solutions in various hydrocarbon oils, particularly for the refining of lubricating oil stocks, burning oils and the like. While a number of selective solvents are in actual commercial use, no solvent has been found to be sufficiently satisfactory for all purposes to retard the general search for improved selective solvents.

We have discovered that certain amine sulfonates are surprisingly effective selective solvents for aromatic hydrocarbons and sulfur compounds in admixture with aliphatic hydrocarbons, notably certain petroleum oil fractions. We have further found that said amine sulfonates can be prepared relatively cheaply, have relatively low toxicity, have relatively mild corrosive properties, permitting their employment in conventional equipment, are characterized by surprisingly low or negligible solubility thereof in the raffinate phase produced by the extraction process, are readily recoverable, and have physical properties which enable them to be employed as selective extraction solvents for aromatic hydrocarbons and sulfur compounds at readily attainable temperatures and pressures. Moreover, said amine sulfonates are characterized by surprisingly great thermal stability permitting their employment as solvents in extractive distillation processes.

It is an object of this invention to provide a process for the selective extraction of aromatic hydrocarbons and organic sulfur compounds from their mixtures with aliphatic hydrocarbons, including both acyclic and alicyclic hydrocarbons which may be completely saturated or may contain one olefinic unsaturation per molecule. Another object of this invention is to provide the art of selective extraction of aromatic hydrocarbons and organic sulfur compounds with novel solvents, viz., certain amine sulfonates. An additional object of our invention is to provide solvents for selective extraction processes char-

2

acterized by high selectivity for aromatic hydrocarbons and organic sulfur compounds while at the same time exhibiting little or no solvent capacity for aliphatic hydrocarbons, both saturated and unsaturated. A further object of our invention is to provide the art with a novel selective extraction process. These and other objects of our invention will be readily discerned from the ensuing description thereof and from the appended figure.

The novel solvents employed in the selective extraction process of this invention are amine sulfonates having the general formula:

wherein R_1 and R_2 are selected from the class consisting of hydrogen and saturated hydrocarbon radicals, R_3 is a saturated hydrocarbon radical containing at least two carbon atoms, and R_4 is selected from the class consisting of saturated hydrocarbon radicals and aromatic hydrocarbon radicals. Thus, the saturated hydrocarbon radical may be an alkyl radical containing at least two carbon atoms, a cycloalkyl radical, a cycloalkyl-alkyl radical, or an aralkyl radical.

R_4 may be an alkyl, cycloalkyl, cycloalkyl-alkyl, aralkyl, aryl, alkaryl or cycloalkyl-aryl radical. The amine sulfonate solvents of this invention contain between 4 and 20 carbon atoms, inclusive, per molecule.

Examples, given by way of illustration and not necessarily for limitative purposes, of suitable alkyl radicals are: ethyl, methyl, n-propyl, isopropyl, n-butyl, amyl, octyl, nonyl, hexadecyl and octadecyl.

Illustrative examples of suitable cycloalkyl radicals include cyclopentyl, methylcyclopentyl, cyclohexyl, methylcyclohexyl, dimethylcyclohexyl, ethylcyclohexyl, ethylcyclopentyl, and endomethylenecyclohexyl (bicyclo [2,2,1] heptyl) and 2-methyl-bicyclo [2,2,1] heptyl.

Examples of suitable aralkyl radicals in the above general formula include benzyl, 2-phenylethyl, 2-phenylpropyl, *w*-xylyl, naphthomethyl, and the like.

Examples of suitable cycloalkyl-alkyl radicals include cyclohexymethyl, cyclohexyethyl, cyclopentylpropyl, and the like.

Examples of suitable R_4 aryl radicals include phenyl, naphthyl and derivatives containing nuclearily substituted chlorine atoms, etc.

Examples of suitable R_4 alkaryl radicals for substitution in the above general formula are

tolyl, xylyl, dimethylphenyl, ethylphenyl, isopropylphenyl, butylphenyl, methylnaphthyl, dimethylnaphthyl, and the like.

Examples of suitable cycloalkyl-aryl radicals include cyclohexylphenyl, methylcyclopentylphenyl, cyclohexyltolyl, and the like.

It is not intended to imply that all the amine sulfonates contemplated for use in this invention are precisely equivalent and indeed the specific examples hereinafter presented demonstrate that they are not. However, they are all generally useful and suitable for the purposes of the claimed invention.

Certain properties of some of the amine sulfonates which are useful for the purposes of the present invention are shown in the following table:

TABLE I
Amine sulfonate

Amine Radical	Sulfonic Acid Radical	M. P. °C.
Triethylamine	Methane	+35
Do	Ethane	-43
Mono-n-butylamine	do	40-60
Tri-n-butylamine	do	40-60
Triethylamine	Mixed C ₁ -C ₄	-48
Mono-n-butylamine	do	40-60

We have found that equal volumes of the salts of Table I and the following solvents are miscible at 20-25° C.: water, methanol, 95% ethanol, acetone and benzene, and that the salts are insoluble in hexane.

We have discovered that certain triethylamine sulfonates are particularly desirable for the purposes of the present invention because they are relatively non-viscous, non-volatile liquids at normal temperature, exhibit high selectivity for automatic hydrocarbons and sulfur compounds, and are characterized by relatively little change of viscosity with temperature. Certain properties of triethylamine salts of the lower alkane-sulfonic acids which are particularly desirable for employment in the claimed process are set forth in Tables II and III.

TABLE II
Properties of triethylamine salts of alkane-sulfonic acids

Pour Point, °F.	-55	-50	-50	-65

The amine sulfonates defined by the above general formula are either normally liquid or relatively low melting solids and may be used for the purposes of the present invention without auxiliary solvents or diluents. However, because of their solubility in water, methanol, ethanol, etc., it may be desirable to employ the amine sulfonate solvents of the present invention together with more or less of such diluents or co-solvents, to modify the selectivity of the amine sulfonates, to lower their melting points, or for other reasons. The amount of auxiliary solvents employed can be selected with reference to specific cases; ordinarily, only between about 1 and about 20 weight per cent based on the amine sulfonate will be employed. If desired, the amine sulfonates may be employed together with between about 1 and about 20 per cent of a sulfonic acid, preferably the sulfonic acid that is combined in the amine sulfonate.

In the process of the present invention the selective solvent is employed as a liquid, melt or solution; the feed stock may be charged to the process as a liquid, solution or vapor. The present invention, therefore, relates to liquid-liquid or liquid-vapor extraction processes employing the above-defined amine sulfonate solvents. When the feed stock is charged to the process as a vapor, the process is one of extractive distillation.

By the term "extraction," as employed in the appended claims, it is intended to include not only liquid-liquid extraction processes, but also extractive distillation employing the above-defined solvents. It is well appreciated that these processes differ somewhat from each other in efficiency or applicability in specific instances, but they are actually and theoretically related (note, for example, H. J. Hibshman, Ind. Eng. Chem. 41, 1366 (1949)).

In general, the extraction operations of the present invention are conducted at temperatures between about 0 and about 180° F., the particular extraction temperature depending upon the specific amine sulfonate solvent, the melting point of the solvent, whether or not it is used alone or with an auxiliary solvent or diluent, the degree and selectivity of extraction sought to be effected, etc.

The volume of selective solvent employed depends, among other things, upon the aromatic and/or sulfur content of the feed stock, the temperature of operation, and desired efficiency, but will generally fall within a range of about 0.3 to about 10 volumes of amine sulfonate per volume of charging stock. Usually, pressures within the range of about 0 to 100 p. s. i. g. are sufficient for this purpose, it being appreciated that the particular pressure necessary in a given case can readily be determined. When the feed stock is to be employed in the vapor phase, suitable pressures can readily be determined at which the feed stock will be a vapor at the extraction temperature.

Numerous hydrocarbon oil fractions derived from petroleum, coal, shale, etc., are known to contain aromatic hydrocarbons, organic sulfur compounds, and usually both of these constituents, whose removal is in numerous instances, desired in order to produce refined hydrocarbon oils. Such oils may boil within the boiling ranges of gasoline, naphtha, kerosene, gas oil, heater oil, or lubricating oil. The process of the present invention is particularly applicable to the refining of gasoline boiling range hydrocarbon oils con-

taining aromatic hydrocarbons and organic sulfur compounds, particularly thioethers or, in the case of sweetened gasolines, alkyl disulfides, and is particularly applicable to such oils containing a substantial proportion of mono-olefinic hydrocarbons, as in the case of sweetened or unsweetened gasolines derived from sulfur-bearing crude oils, such as West Texas crude oil, by cracking or coking processes. The process of the present invention is particularly applicable to the selective extraction of polycyclic aromatic hydrocarbons, for example, mono- and dimethyl-naphthalenes, from hydrocarbon fractions containing the same, for example, hydroformer bottoms fractions and cracked gas oil boiling range stocks derived from the cracking of gas oil or higher boiling range hydrocarbon oils in the presence of silica-alumina, silica-magnesia, or similar solid siliceous cracking catalysts, etc. The process of the present invention is well adapted for the selective extraction of non-acidic sulfur compounds, such as thioethers, disulfides and cyclic sulfides, such as thiophene, alkylthiophenes, thiophanes, and the like.

Following are some specific examples of the process of our invention, which are furnished to illustrate, but not unduly to limit, the scope of our invention.

EXAMPLE 1

One volume of a mixture containing 0.5 volume of benzene and 0.5 volume of n-heptane was contacted with one volume of mixed alkane-sulfonic acid salts (C₁-C₄ alkanesulfonic acid mixture) of n-butyl amine at 35° C. The mixture was shaken and then allowed to settle into two layers. The amine salt layer consisted of 1.22 volumes and the hydrocarbon layer of 0.78 volume. The oil was recovered from the extract by dilution of the extract phase with about an equal volume of water. The data summarized below show that the extract contained 62% benzene and 38% heptane and the raffinate contained 33% benzene and 67% heptane.

	Charge	Extract	Raffinate
$n_{D^{20}}$	1.4397 0.769	1.4573 0.806	1.4243 0.749

EXAMPLE 2

When the process of Example 1 was repeated, employing, in the place of the solvent of Example 1, one volume of a mixture of 0.8 volume n-butylamine C₁-C₄ alkanesulfonates, and 0.2 volume of methanol, at 23° C., the identical extraction results were obtained.

EXAMPLE 3

One volume of the mixture of equal parts of n-heptane and methyl disulfide was extracted at 40° C. with one volume of n-butylamine C₁-C₄ alkanesulfonates. The extraction mixture was allowed to stratify into a raffinate layer containing 41.2% methyl disulfide and 58.8% heptane and an extract layer consisting of 62.8% methyl disulfide and 37.2% of heptane, by volume.

EXAMPLE 4

The feed stock was a light catalytic cycle stock derived from the catalytic cracking of West Texas gas oil in the presence of natural clay catalyst and having the following properties:

$n_{D^{20}}$ ----- 1.4963
Weight per cent S----- 1.15
Specific Dispersion----- 156
Bromine No----- 11.3
20 ° A. P. I.----- 29.3

One volume of the catalytic cycle stock was mechanically stirred with one volume of triethylamine ethanesulfonate for 15 minutes at 70° C. Agitation was discontinued and the contacting mixture was allowed to separate by gravity into an upper raffinate layer and a lower extract layer, whose volume was 11.5 volume percent, based on the feed. The following data were obtained:

	$n_{D^{20}}$	Percent S
Catalytic cycle stock charge-----	1.4963	1.15
Raffinate-----	1.4854	0.85
Extract-----	1.5711	3.26

As a measure of the selectivity of the solvents for the extraction of aromatic hydrocarbons, the following factor, termed the aromatic selectivity factor (ASF) has been developed:

$$ASF = \frac{n_{D^{20}} \text{ feed} - n_{D^{20}} \text{ raffinate}}{\text{Volume percent extracted} \times 10^{-4}}$$

A similar factor expressing the selectivity of a solvent for sulfur compounds, the so-called sulfur selectivity factor (SSF) is determined in accordance with the following equation:

$$SSF = \frac{\text{percent S in feed} - \text{percent S in raffinate}}{\text{Volume percent extracted} \times 10^{-4}}$$

60 The data in Table IV afford a comparison of the performance of triethylamine ethanesulfonate in cycle stock extraction with that of nitromethane, furfural and liquid hydrogen fluoride, which are among the most highly regarded solvents for the extraction of aromatic and sulfur compounds from the type of feed stock here under consideration:

TABLE IV

	Volume Percent Extract	Arom. Factor	S Factor
Triethylamine ethanesulfonate-----	11.5	95	261
Furfural-----	25	97	269
Nitromethane-----	12	99	262
Liquid HF-----	17.2	87	628

It will be obvious that only the use of nitromethane afforded raffinate yields as high as those attainable by the use of triethylamine ethanesulfonate. It will also be noted that the ASF and SSF of the amine sulfonate solvent compare very favorably with those of furfural and nitromethane. The amine sulfonate was more selective for aromatics than HF, suggesting the sequential

7
employment of the amine sulfonate and HF in refining hydrocarbon oils containing both aromatic hydrocarbons and organic sulfur compounds.

EXAMPLE 5

One volume of the catalytic cycle stock employed as a feed stock in Example 4 was extracted, using the same technique as in Example 4, with an equal volume of molten triethylamine p-toluenesulfonate, a crystalline solid which melts at 65° C. The amount of extract was 10 volume per cent based on the feed stock. The following data were obtained:

TABLE V

	n_{D}^{20}	Percent S
Cycle stock charge.....	1.4963	1.15
Raffinate.....	1.4863	0.92

The above data indicate that the aromatic selectivity factor of the solvent under the above conditions was 104 and the sulfur selectivity factor was 230.

EXAMPLE 6

One volume of the catalytic cycle stock employed as feed stock in the above examples was contacted with two volumes of the n-butylamine salt of a mixture of C₁-C₄ alkanesulfonic acids in two extraction treatments at 50° C. The following data were obtained:

TABLE VI

	n_{D}^{20}	Vol. Percent Charge	Percent S
Catalytic Cycle Stock.....	1.4963	-----	1.15
Final Raffinate.....	1.4963	-----	0.81

Extract 2.....	1.5392	4.5	2.10

The data in the following table show the results obtained when one volume of the light catalytic cycle stock employed as feed stocks in the above examples was extracted with one volume of amine salt at 70° C.

TABLE VII

Example	Extractant	Volume Percent Extracted	Aromatic Selectivity Factor	Sulfur Selectivity Factor
7.....	Mono-n-butylamine Ethanesulfonate.....	8	65	-----
8.....	Di-n-butylamine Ethanesulfonate.....	24	58	146
9.....	Tri-n-butylamine Ethanesulfonate.....	32	58.5	143.5

EXAMPLE 10

One volume of the mixture of 0.525 part by volume of thiophene and 0.475 part by volume of n-heptane was extracted at 25° C. with one volume of triethylamine C₁-C₄ alkanesulfonates. The extraction mixture was allowed to stratify into a raffinate layer containing 20% by volume of thiophene and 80% by volume of n-heptane, and an extract layer from which an oil was separated by dilution with water, said oil containing 93% by volume of thiophene and 7% by volume of n-heptane. The raffinate yield was 56% of the feed stock.

An illustrative process flow and equipment are

indicated in the figure. The hydrocarbon mixture to be extracted, containing aromatic hydrocarbons and/or sulfur compounds, for example, a light cycle stock from silica-alumina cracking of a West Texas gas oil, is passed through valved line 18 into the contacting zone 11.

10 We may employ conventional contacting and separation equipment such as has heretofore been employed in effecting selective solvent extraction of lubricating oils, illuminating oils, etc., or in the processes for the extractive distillation of hydrocarbon oils. The contacting equipment may comprise a vertical tower, which is preferably provided with packing or spacing materials 15 to insure thorough contacting of the hydrocarbon feed stock and the amine sulfonate solvent. Suitable materials of construction for the contacting zone are aluminum and stainless steel, which have proven strongly resistant to corrosion by alkyl ammonium sulfonates, although it should be understood that we may employ other construction materials, for example, glass-, ceramic- or carbon-lined iron towers. Suitable spacing materials comprise shaped fragments, for 20 example Berl saddles or Raschig rings made of carbon, porcelain, glass, aluminum, stainless steel, etc.; stainless steel jack chain; stainless steel or aluminum screens which may be shaped, for example, in the form of Scofield, McMahon or Stedman packing, etc. If desired, the contacting tower may be jacketed or provided with heat exchange coils to permit maintenance of the desired temperature.

25 In a desirable method of operation, the feed stock is passed into the lower portion of zone 11 against a counter-flow of an amine sulfonate, for example, triethylammonium ethanesulfonate, which is introduced into the upper portion of tower 11 through valved line 12. Diluents, e. g., 30 pentane or hexane, or modifying solvents, e. g., methanol, may be introduced with the feed stock, the amine sulfonate solvent or separately through a line not shown, into zone 11.

35 The contacting of the amine sulfonate and hydrocarbon feed stock results in the production 40 of raffinate and extract phases whose common boundary or interface is indicated at 13. The countercurrent extraction zone may be operated with either the feed stock or solvent as the continuous phase. In the mode of operation, illustrated in the figure, the extract phase is shown 45 as the continuous phase through which the hydrocarbon feed stock is introduced as the dispersed phase.

50 The raffinate phase forms a supernatant layer above interface 13 in zone 11 whence it is discharged from said zone through valved line 14. The raffinate phase contains a substantially reduced content of aromatic and sulfur compounds 55 as compared with the feed stock. It should be understood, however, that the raffinate phase may be further treated to reduce its content of sulfur and aromatic compounds, if it is so desired. For this purpose, a portion at least of the raffinate phase may be recycled from line 55 60 65 70 75 80 85 90 95 100 105 110 115 120 125 130 135 140 145 150 155 160 165 170 175 180 185 190 195 200 205 furfural, bis-(beta-chloroethyl) ether, etc. It should be noted that further extraction of the raffinate passing through line 14 with solvents different from the amine sulfonate passing through line 12 is greatly facilitated by the fact that the amine sulfonate is substantially insoluble in said raffinate, averting the necessity of special procedures for the removal of said amine sulfonate from said raffinate. The inappreciable solubility of the amine sulfonates of this invention in the raffinate phase is noteworthy and substantially different from the behavior heretofore observed in extraction processes employing conventional solvents, such as phenol, furfural, nitromethane, etc.

The extract phase, a solution of aromatics and/or sulfur compounds in the amine sulfonate solvent, is withdrawn from the lower end of tower 11 through valved line 15, whence it is passed into separation zone 16. If desired, a part of the extract phase may be recycled from line 15 to feed line 12 by means of a line not shown in the drawing. Zone 16 may be a separating vessel into which water or aqueous solvents are introduced by valved line 17, in suitable amounts, e. g. between about 0.5 and about 3.0 volumes per volume of extract, to effect the resolution of the extract into an aqueous amine sulfonate layer and a layer of aromatic hydrocarbons and/or organic sulfur compounds. Alternatively, the separation zone 16 may take the form of a distillation vessel, preferably a steam distillation vessel in which the aromatic and/or sulfur compounds are vaporized and pass overhead, usually as azeotropes with water, through line 18 into a settling vessel 19, whence the water layer is withdrawn through valved line 20 and aromatics and/or sulfur compounds are withdrawn through valved line 21.

A bottoms fraction containing the amine sulfonate is withdrawn from zone 16 through valved line 22 for recycle to line 12 and extraction zone 11. The amine sulfonate stream withdrawn from zone 16 may be purified before recycle to contacting zone 11, for example, by blowing with hot inert gases such as flue gas, nitrogen, carbon dioxide, or other inert gas to effect substantial dehydration thereof, in a step not shown in the drawing, following which the treated amine sulfonate may be recycled to extraction zone 11. Alternatively, the recycle stream of amine sulfonate may be dehydrated by azeotropic distillation of water therefrom with various azeotropic agents, e. g. benzene, toluene, n-heptane, etc. At least partial dehydration of the recycled solvent is necessary when the extract is sprung by means of water or wet steam.

Although the figure represents a continuous countercurrent, single-stage extraction operation, it will be apparent that the process of the present invention is amenable to batch processing, multi-stage operation, concurrent flow of solvent and feed stock, the use of knot-hole or other mechanical mixers for feed and solvent in series with one or more settling zones and other variations that will no doubt occur to those skilled in the art, without departing from the spirit of this invention.

Having thus described the process of our invention, what we claim is:

1. A process for the selective extraction of a compound selected from the class consisting of aromatic hydrocarbons and organic sulfur compounds from a mixture comprising a compound of said class and an aliphatic hydrocarbon, which

process comprises contacting said mixture with a selective solvent consisting essentially of an amine salt of a sulfonic acid, said salt having the formula

wherein R₁ and R₂ are selected from the class consisting of hydrogen and saturated hydrocarbon radicals, R₃ is a saturated hydrocarbon radical containing at least two carbon atoms, and R₄ is selected from the class consisting of saturated hydrocarbon radicals and aromatic hydrocarbon radicals, said amine salt containing between 4 and 20 carbon atoms, inclusive, per molecule, and separating an extract phase comprising said selective solvent and a compound of said class.

2. The process of claim 1 wherein said mixture comprises a light cracked gas oil containing polycyclic aromatic hydrocarbons and sulfur compounds, said gas oil being derived by cracking high boiling hydrocarbon oils containing sulfur and aromatic compounds in the presence of a solid siliceous cracking catalyst.

3. A process for the selective extraction of an aromatic hydrocarbon from a mixture of said hydrocarbon with an aliphatic hydrocarbon, which process comprises contacting said mixture with a selective solvent consisting essentially of an amine salt of a sulfonic acid, said salt having the formula

wherein R₁ and R₂ are selected from the class consisting of hydrogen and saturated hydrocarbon radicals, R₃ is a saturated hydrocarbon radical containing at least two carbon atoms, and R₄ is selected from the class consisting of saturated hydrocarbon radicals and aromatic hydrocarbon radicals, said amine salt containing between 4 and 20 carbon atoms, inclusive, per molecule, and separating an extract phase comprising said selective solvent and said aromatic hydrocarbon.

4. A process for the selective extraction of an organic sulfur compound from a mixture comprising said sulfur compound and an aliphatic hydrocarbon, which process comprises contacting said mixture with a selective solvent consisting essentially of an amine salt of a sulfonic acid, said salt having the formula

wherein R₁ and R₂ are selected from the class consisting of hydrogen and saturated hydrocarbon radicals, R₃ is a saturated hydrocarbon radical containing at least two carbon atoms, and R₄ is selected from the class consisting of saturated hydrocarbon radicals and aromatic hydrocarbon radicals, said amine salt containing between 4 and 20 carbon atoms, inclusive, per molecule, and separating an extract phase comprising said selective solvent and said organic sulfur compound.

5. A process for the selective extraction of a compound selected from the class consisting of aromatic hydrocarbons and organic sulfur compounds from a mixture comprising a compound of said class and an aliphatic hydrocarbon, which process comprises contacting said mixture with a

11

selective solvent consisting essentially of a triethylamine salt of an alkanesulfonic acid containing from 1 to 4 carbon atoms, inclusive, per molecule, and separating an extract phase comprising said selective solvent and a compound of said class.

6. A process for the selective extraction of a compound selected from the class consisting of aromatic hydrocarbons and organic sulfur compounds from a mixture comprising a compound of said class and an aliphatic hydrocarbon, which process comprises contacting said mixture with a selective solvent consisting essentially of the triethylamine salt of p-toluenesulfonic acid, and separating an extract phase comprising said selective solvent and a compound of said class.

7. A process for the selective extraction of a compound selected from the class consisting of aromatic hydrocarbons and organic sulfur compounds from a mixture comprising a compound of said class and an aliphatic hydrocarbon, which process comprises contacting said mixture with between about 0.3 and about 10 volumes, per volume of said mixture, of a selective solvent consisting essentially of an amine salt of a sulfonic acid, said salt having the formula

12

wherein R_1 and R_2 are selected from the class consisting of hydrogen and saturated hydrocarbon radicals, R_3 is a saturated hydrocarbon radical containing at least two carbon atoms, and R_4 is selected from the class consisting of saturated hydrocarbon radicals and aromatic hydrocarbon radicals, said amine salt containing between 4 and 20 carbon atoms, inclusive, per molecule, effecting said contacting at a temperature between about 0° C. and about 180° C. under a pressure sufficient to maintain said mixture and said selective solvent in the liquid phase, and separating an extract phase comprising said selective solvent and a compound of said class.

8. The process of claim 3 wherein R_4 is a saturated hydrocarbon radical.

9. The process of claim 3 wherein R_4 is an aromatic hydrocarbon radical.

10. The process of claim 4 wherein R_4 is a saturated hydrocarbon radical.

11. The process of claim 4 wherein R_4 is an aromatic hydrocarbon radical.

12. The process of claim 7 wherein R_4 is a saturated hydrocarbon radical.

13. The process of claim 7 wherein R_4 is an aromatic hydrocarbon radical.
